Harry S. Schroeder
ATTORNEY

UNITED STATES PATENT OFFICE

BYNUM B. McCROSKEY, OF OAKLAND, CALIFORNIA

PROPELLER

Application filed May 27, 1930. Serial No. 456,118.

The invention is for a propeller and has special reference to the retracted vane type of air propeller to be used for the propulsion of air craft and for similar purposes.

5 The object of the invention is to provide a propeller which may be adjusted while in operation to react in any desired direction transversely of the axis, whereby the propeller may be quickly changed to provide traction, repellency, lifting or depression or combinations other than opposites.

Another object of the invention is to provide a propeller as outlined which is light in weight and economically constructed as 15 many of the parts may be made in the form of sheet metal stampings.

Other objects of the invention will become apparent as the following description is read in connection with the drawings forming a 20 part of this specification.

The invention consists of a pair of spaced discs concentrically mounted, with an interposed eccentric or cam adjustable by means of a shaft extending through one hub of the 25 discs, the other hub being driven by a source of power, a plurality of vanes pivoted at their rearward ends between the discs adjacent the periphery, the forward end of the vanes being restrained by connecting rods 30 governed by the eccentric or cam, whereby, as the discs are revolved, with the cam or eccentric held stationary, the vanes are forced outward and withdrawn with each revolution of the discs. The eccentric or cam being 35 adjustable about its center permits reaction of the vanes in any direction transverse to the axis of the propeller.

Referring to the accompanying drawings in which

40 Fig. 1 is a longitudinal sectional elevation through the propeller, bearing and adjusting means;

Fig. 2 is a transverse sectional elevation through the propeller.

45 Similar reference characters are used to designate similar parts throughout the several views.

The propeller consists of a pair of dished discs 3 and 4 concentrically mounted on hubs 50 5 and 6 by any known method, indicated as

bolted at 7 to a flange integral with the hubs 5 and 6. The vanes consists of sheet metal members formed to U shape and having front 8 and sides 9 and 10, the sides 9 and 10 being pivotally mounted between the discs 3 and 55 4 as at 11. Adjacent the front 8 of the vanes, connecting rods 12 are pivotally connected as at 13, the opposite end being pivotally connected at 14 to a ring 15 mounted on the outer race of a ball bearing 16, one pair of connecting rods 17 being rigidly fixed to the ring 15 as indicated at 18 and providing thereby 60 master rods. The ball bearing 16 is mounted on a crank 19 constituting a part of the crank-shaft 20, which extends into the hub 5 and through the hub 6 and is rotatable therein. The crankshaft 20 may readily be replaced by a cam shaft and internal cam and having 65 rollers cooperating with the cam surface and replacing the pivots 14 on the connecting rods 12. 70

The adjustment is indicated as consisting of a worm gear 21 fixed on the crankshaft 20 and meshing with a worm 22 and operated by 75 a handwheel 23.

The propeller may be driven in any suitable manner, indicated as bevel gears 24 and 25, the gear 24 being fixed on the end of hub 5.

Suitable bearings 26 are provided for the 80 hubs 5 and 6.

In operation, referring to Fig. 2 with the propeller revolving counter-clockwise, the propeller would travel to the right. By adjusting the crank about through an angle of 85 ninety degrees counter-clockwise, the vanes would be projected at the left side and withdrawn at the right, thereby providing lifting, while a further adjustment of ninety degrees would cause the vanes to be projected 90 below and withdrawn above, thus driving to the left with a reversal of motion from that indicated in the figure.

Having described an operative method of 95 constructing and using the invention, it will be understood that variations in construction, design and arrangement of parts which are consistent with the appended claims may be resorted to without departing from the 100

spirit or scope of the invention or sacrificing any of the advantages thereof.

I claim:—

1. A propeller comprising a pair of oppositely disposed, spacedly related, rotatably mounted, dished discs having a plurality of interposed equi-angularly spaced U shaped vanes pivotally mounted adjacent the ends of the legs thereof, connecting rods pivotally connected to said legs adjacent the cross member, a crank shaft concentrically mounted relative to said discs and rotatable in the hubs thereof and having the crank interposed between said discs, a collar rotatably mounted on said crank, said connecting rods being pivotally connected to said collar except from one of said vanes being fixedly connected and comprising a master rod, means for driving said propeller, and means for rotatably adjusting said crankshaft.
2. A propeller comprising a pair of disks spacedly related and having hubs rotatably mounted in bearings, a crankshaft rotatably mounted in said hubs, means for adjusting the crank position of said crankshaft, a plurality of U shaped vanes pivotally mounted at the ends of the legs thereof between said disks, a ball bearing on the crank of said crankshaft, a collar fixedly secured on the outer race thereof and rods pivotally connected to the legs of the vanes adjacent the cross member thereof, one of said rods being fixedly connected to said collar, the others of said rods being pivotally connected thereto.
- 35 In testimony whereof I have affixed my signature.
